UNITED STATES PATENT OFFICE.

GEORGE W. GARDNER, OF DAWKINS, COLORADO.

DESIGN FOR A GAME-BOARD.

SPECIFICATION forming part of Design No. 22,790, dated September 19, 1893.

Application filed July 24, 1893. Serial No. 481,354. Term of patent 3½ years.

To all whom it may concern:

Be it known that I, GEORGE W. GARDNER, a citizen of the United States, residing at Dawkins, in the county of Pueblo and State of Colorado, have invented a new and original Design for Game-Boards, of which the following is a specification.

The invention relates to a new and original design for a game board.

- 10 The object of the present invention is to provide an attractive game board; and the essential feature resides in a game board provided with series of squares and having within the squares series of circles.
- 15 The figure of the drawing is a plan view of a game board showing my new and original design.

Referring to the drawing, 1 designates a game-board having an outer marginal square 2 and an inner series of squares 3, 4 and 5. The marginal square or rectangle has arranged at the center of its sides circles 6; and the square or rectangle 3 of the inner series

located adjacent to the marginal square or rectangle 2 has at the corners circles 7. The 25 sides of the different squares are parallel and it will be apparent that the game board presents an ornamental and attractive appearance.

What I claim is—

The design for a game board herein shown and described the same comprising a board having an outer marginal square, an inner series of squares arranged one within another, a series of outer circles arranged at the 35 centers of the sides of the outer marginal square, and a series of inner circles arranged at the corners of the square adjacent to the outer marginal one, as set forth.

In testimony that I claim the foregoing as 40 my own I have hereto affixed my signature in the presence of two witnesses.

GEORGE W. GARDNER.
